UNITED STATES PATENT OFFICE.

RUSSELL W. MAGNA, OF HOLYOKE, MASSACHUSETTS.

VALVE-CAGE REMOVER.

Application filed October 9, 1920. Serial No. 415,785.

To all whom it may concern:

Be it known that I, RUSSELL W. MAGNA, citizen of the United States, residing at Holyoke, in the county of Hampden and 5 State of Massachusetts, have invented new and useful Improvements in Valve-Cage Removers, of which the following is a specification.

This invention relates to an improvement 10 in valve-cage removers for removing valve-cages of valve-in-head engines.

It is well known that such valve-cages, due to corrosion, deposit of carbon, etc., often stick very tightly in their seats and 15 require considerable force to remove them. The difficulty heretofore in removing such valve-cages without injury to the valve or its parts, is in obtaining a direct pull upward on the cage in a direction coaxial with its 20 path of movement. The usual method of prying upwardly upon the valve-spring or valve-spring seat with a screw-driver or other tool is an inefficient application of power and not only mars the appearance of 25 the parts, but also tends to bend the valve-stem out of line or injure the valve-spring.

The salient feature of the present improvement lies in providing means for obtaining a positive connection with the valve- 30 stem without injury to the stem and in applying the lifting force to remove the valve-cage substantially in line with the valve-stem, thus avoiding any tendency to bend or distort the parts of the valve-cage and 35 valve.

For accomplishing this object, I have provided what may be broadly termed a double jacking-mechanism,—one jacking-mechanism operative to force a positive en- 40 gagement between the lifting means and the valve-stem, preferably by an engagement beneath the valve-stem key, and the second jacking-mechanism operative to lift the valve and its surrounding cage from the 45 valve-cage seat.

I appreciate that this broad principle of operation may be carried out by various forms of specific mechanism and therefore do not wish my invention to be limited to 50 the preferred embodiment of the invention herein described and shown.

Referring to the drawings,—

Fig. 1 is a section along line 1—1 of Fig. 2 through a portion of an engine head and the 55 jack-frame of the valve-cage remover, show-

ing other parts of the remover and valve in elevation;

Fig. 2 is a side elevation of the remover, looking in the direction of the arrow in Fig. 1, with a portion of the jack-frame cut away 60 to show the enclosed parts in elevation;

Fig. 3 is a detail section of the valve-stem-engaging elements;

Fig. 4 is a similar view of the valve-stem-engaging elements in a different position: 65

Fig. 5 is a detail cross-section through the line 5—5 of Fig. 3; and

Fig. 6 is a detached view of a hook-member of the hook-device.

Referring more particularly to the drawings,—1 indicates the engine head having the usual opening therethrough to receive the valve-cage 2 which has its seat upon a shoulder 3 of the engine head opening. The valve-cage 2, in the form of a cylindrical shell, has a tubular guide 4 for the stem 5 of the valve 6. The valve 6 is held to its seat 7 on the valve-cage by the usual valve-spring 8 compressed between the valve-cage 2 and the valve-spring seat 9, which is held on the end of the valve-stem by the valve-stem key 10. The valve-cage is retained in the engine head opening by a suitable retaining-nut (not shown) in screw-threaded engagement with the threads 11 at the upper end of said engine head opening. The above-mentioned parts are of usual construction and need not be further described.

The remover comprises an outer or jack-frame 12 for resting on the engine head and an inner casing 13 supported within the jack-frame, said casing 13 having means associated therewith for connective engagement to the valve-stem, as will be hereinafter described. The casing 13, when connected to the valve-stem, is lifted with respect to the jack-frame 12 by a suitable jacking-mechanism, to lift and remove the valve-cage. The jacking-mechanism for lifting the casing 13 comprises a screw 14 in screw-threaded engagement with the head 15 of said casing 13 and having a nut 16 in threaded engagement with the upper portion thereof. The screw 14 is provided with a cross-piece 14^a at its upper end so that it may be turned by hand 100 in the head 15 independently of the nut 16, for a purpose hereinafter described. The nut 16 is formed with a flange or disk portion 17 adapted to bear against the upper end of the jack-frame 12, and said nut has a 105

handle 18 whereby it may be turned upon the screw 14 to raise the same, together with the casing 13 carried thereby, in the usual manner of jacking-mechanism.

5 The elements carried by the casing 13 for connective engagement with the valve-stem will now be described. A hook-device is mounted within the side walls of the casing, which hook-device comprises, preferably, four separate hook members 19, 19^a, 19^b and 19^c, each of the form shown in Fig. 6. The hook members are preferably arranged in pairs,—19 and 19^b at one side of the casing 13, and 19^a and 19^c at the other side of said casing (see Fig. 5), said pairs of hook members being oppositely disposed in facing relation, as shown in Figs. 1, 3 and 4. Each hook-member, as shown in Fig. 6, is formed with a straight slot 20 at its upper end and a slot 21 at its lower end having both a straightaway portion and a curved portion, as shown, and each hook-member is also formed with an open-ended notch 22 intermediate its slots, together with 25 a hook 23 at its lower end.

Cross-pins 24, 25, 26 and 27 connect opposite sides of the casing 13, and slidably mounted upon the pins 24 and 25 are the hook-members 19 and 19^b by having the cross-pins 24 and 25 passing through the slots 20 and 21 of said hook members. Similarly, the hook-members 19^a and 19^c are slidably mounted upon the pins 26 and 27. It will be observed that the hook portions 23 of the hook-members 19^a and 19^c are adapted to engage, each under a separate end of the valve-stem key 10 (see Fig. 2) for a balanced hold thereon, and that the oppositely-facing hook-members 19 and 19^b similarly engage respective separated ends of the valve-stem key, so that said oppositely-facing hook portions cooperate in effecting a positive engagement beneath the key 10 of the valve-stem 5, as shown in Fig. 4.

45 The hook-members 19, 19^a, 19^b and 19^c are adapted to be moved upwardly and downwardly within the casing 13 by means of the screw 14, which carries a washer 28 fixed at its lower end, for extending within all of 50 the notches 22 of said hook-members. The notches 22 are slightly wider than the thickness of the washer 28, to permit a slight swinging movement of the hook-members when guided upwardly and downwardly by 55 the cam means consisting of the slots 20 and 21 and pins 24, 25, 26, and 27.

Pivottally mounted within the casing 13 is a pair of gripping jaws 29 and 30,—the jaw 29 being hung on the cross-pin 25 and located between the hook-members 19 and 19^b, the jaw 30 being hung on the cross-pin 27 and located between the hook-members 19^a and 19^c (see Fig. 5). The gripping jaws 29 and 30 are each split at their upper ends 60 and carry therein adjustable bearing-studs

33 and 34 respectively. Clamping screws 31 and 32 are provided to close the split ends of the jaws upon the adjusted bearing studs. Each bearing-stud preferably comprises a screw carrying at its inner end a ball 35 for 70 frictional bearing engagement with a cam-collar 36 mounted upon the screw 14. The cam-collar 36 is slidably mounted upon a reduced portion of the screw 14 and is normally held up against a shoulder 37 on said screw 14 by a coiled spring 38 surrounding the screw and interposed between said cam-collar 36 and the washer 28. The lower portion of each gripping jaw 29 and 30 is preferably formed with gripping teeth 39 for 80 gripping engagement with the upper end of the valve-stem.

The operation of the valve-cage remover is as follows: The parts, assembled as shown in Fig. 1, are placed over the valve with the 85 jack-frame 12 resting upon the engine head 1. The first action is to connectively engage the casing 13 with the stem of the valve, and this connection is effected as follows: The hook-device comprising the hook-members, 90 together with the opened gripping jaws, are thrust down over the end of the valve-stem 5 until the lower ends of the hook-members 95 abut the valve-spring seat 9. Thereupon, the screw 14 is turned by its cross-piece 14^a so as to screw downwardly through the head 15 of the frame 13. The downward movement of the screw 14 carries the cam-collar 36 between the bearing-studs 33 and 34, acting to spread the upper ends of said gripping jaws 29 and 30 and swing the same upon the pivot-pins 25 and 27, to firmly grip the lower toothed ends of said jaws upon the upper end of the valve-stem 5.

The valve-stem being thus firmly gripped by the jaws 29 and 30, the continued downward movement of the screw 14 slides the hook-members downwardly upon the guiding pins 24—25, first in a straight-line direction in accordance with the straight-away portions of the guide-slots 20 and 21, which downward movement of the hook-members against the valve-spring seat 9 compresses the valve-spring 8, as shown in Fig. 3. The further downward movement of the hook-members eventually brings the curved portion of the slots 21 to the guiding-pins 25 and 27, to effect an inward swing of the lower hooked ends 23 of the hook-members beneath the valve-stem key 10, as shown in Fig. 4.

The cam-collar 36 is preferably so designed that immediately after the hook-members have engaged beneath the valve-stem key 10, as shown, it will release the 125 jaws 29 and 30 from gripping engagement with the valve-stem, this being accomplished by the bearing members 33 and 34 of said jaws arriving at the upper side of said cam-collar 36, as shown in Fig. 4.

It will be observed that the operation above described is, in effect, a jacking action in which the grip of the jaws 29 and 30 upon the valve-stem 5 acts as a purchase for enabling the hook-members to be forced downward against the tension of the valve-spring 8 in order to engage beneath the valve-stem key 10.

The hook-members having been thus engaged beneath the valve-stem key 10, the next action is to operate the second jacking-mechanism for lifting the valve-stem with its valve-cage out of the engine head opening. This is accomplished by screwing the 15 nut 16 downwardly on the screw 14 until its flange 17 bears against the jack-frame 12, whereupon a continued screwing action of the nut 16 will raise the screw 14 with the casing 13 and the hook-members carried 20 thereby.

An advantageous feature of the present device is that the raising movement of the casing 13 lifts the hook-members by means of the cross-pins 25 and 27 bearing against 25 the upper curved ends of the slots 21 in said hook-members, thereby causing the lifting force to act in a manner to swing the lower hooked ends 23 even more firmly toward one another so that there is no possibility of 30 their becoming disengaged from the valve-stem key 10.

After the valve-cage has been removed, the hook-members may be disengaged from beneath the valve-stem key in a manner to 35 avoid injury to the valve-stem or gripping jaws, and it is for this purpose that the cam-collar 36 is slidably mounted upon the screw 14 and yieldingly held upwardly in its position by the spring 38. In disengaging the 40 hook-members from the valve-stem key 10, the screw 14 is backed off, to slide the hook-members upwardly relative to the casing 13 and cross-pins 24, 25, 26, 27, the lower slots 21 acting, of course, on the pins 25 and 27, 45 to gradually spread or open the hook portions 23. In this upward travel of the screw 14 relative to the casing 13 and jaws 29, 30, in disengaging the hook-members, the cam-collar 36 is not carried upwardly with the 50 screw, as otherwise it would again act on the bearing-studs 33 and 34 to grip the jaws 29 and 30 upon the valve-stem, and thus either wear out the teeth of the jaws or injure the valve-stem by sliding over the same 55 in gripped contact. The cam-collar 36 remains in the position shown in Fig. 4 at the lower side of the stud bearing members 33 and 34 during the backing off of the screw 14, whereby the spring 38 below the cam- 60 collar is slightly compressed. As soon, however, as the hook-members have been entirely disengaged from the valve-stem key 10 and together with the jaws 29—20 are removed from the end of the valve-stem, the lower end 65 of the jaws may then freely swing toward

one another, allowing the compressed spring 38 to thrust the cam-collar 36 upwardly past the stud bearing members 33 and 34 and against the shoulder 37. The parts of the remover are now restored to their initial position ready for a new operation. 70

What I claim is—

1. A valve-cage remover for removing a valve-cage containing a valve and its stem, valve-spring and valve-spring seat, comprising in combination, an element for lifting said valve-stem by engagement therewith above the valve-spring seat, and jacking mechanism for lifting said element and engaged valve-stem. 75

2. A valve-cage remover for removing a valve-cage containing a valve and its stem and valve-stem key, comprising in combination, a lifting element for detachable connection in direct engagement with the key of said valve-stem, and jacking mechanism for lifting said element and engaged valve-stem. 80

3. A valve-cage remover for removing a valve-cage containing a valve and its stem, valve-stem key and valve-spring, comprising in combination, a hook-device, and means to force the same against the tension of said valve-spring to engage beneath the key of said valve-stem. 85

4. A valve-cage remover for removing a valve-cage containing a valve and its stem, valve-stem key and valve-spring, comprising in combination, a hook-device, means to force the same against the tension of said valve-spring to engage beneath the key of said valve-stem, and jacking mechanism for lifting said hook-device and engaged valve-stem key. 90

5. A valve-cage remover for removing a valve-cage containing a valve and its stem, a valve-stem key and a valve-spring, comprising in combination, jaws for gripping said valve-stem, a hook-device, means for forcing said hook-device against the tension of said valve-spring into hooked engagement with said valve-stem key, and jacking mechanism for lifting said hook-device and engaged valve-stem key. 105

6. A valve-cage remover for removing a valve-cage containing a valve and its stem, a valve-stem key and a valve-spring, comprising in combination, jaws for gripping said valve-stem, actuating means for said gripping jaws, a hook-device, means for forcing said hook-device against the tension of said valve-spring into hooked engagement with said valve-stem key, and jacking mechanism for lifting said hook-device and engaged valve-stem key. 115

7. A valve-cage remover for removing a valve-cage containing a valve and its stem, a valve-stem key and a valve-spring, comprising in combination, jaws for gripping said valve-stem, actuating means for said gripping jaws, a hook-device, means for 120

forcing said hook-device against the tension of said valve-spring into hooked engagement with said valve-stem key, said actuating means acting to release said gripping jaws when said hook-device is engaged with said valve-stem key, and jacking mechanism for lifting said hook-device and engaged valve-stem.

8. A valve-cage remover for removing a valve-cage containing a valve and its stem and a valve-stem key, comprising in combination, jaws for gripping said stem, a hook-device, and jacking mechanism employing a gripped engagement of said jaws on said stem as a purchase for forcing said hook-device into hooked engagement with said valve-stem key.

9. A valve-cage remover for removing a valve-cage containing a valve and its stem and a valve-stem key, comprising in combination, jaws for gripping said stem, a hook-device, jacking mechanism employing a gripped engagement of said jaws on said stem as a purchase for forcing said hook-device into hooked engagement with said valve-stem key, and a second jacking mechanism for lifting said hook-device and engaged valve-stem key.

10. A valve-cage remover for removing a valve-cage containing a valve and its stem, a valve-stem key, and a valve-spring, comprising in combination, jaws for gripping said stem, a hook-device, and jacking mechanism comprising means to actuate said jaws into gripping engagement with said stem, said jacking mechanism employing the gripped engagement of said jaws on said stem as a purchase for forcing said hook-device against the tension of said valve-spring into hooked engagement with said valve-stem key.

11. A valve-cage remover for removing a valve-cage containing a valve and its stem, a valve-stem key and a valve-spring, comprising in combination, jaws for gripping said stem, a hook-device, jacking mechanism comprising means to actuate said jaws into gripping engagement with said stem, said jacking mechanism employing the gripped engagement of said jaws on said stem as a purchase for forcing said hook-device against the tension of said valve-spring into hooked engagement with said valve-stem key, and a second jacking mechanism for lifting said hook-device and engaged valve-stem key.

12. A valve-cage remover for removing a valve-cage containing a valve and its stem, and a valve-stem key, comprising in combination, jaws for gripping said valve-stem, a hook-device, means for forcing said hook-device into hooked engagement with said valve-stem key, comprising a screw, and cam means operated by said screw for actuating said gripping jaws.

13. A valve-cage remover for removing a valve-cage containing a valve and its stem, and a valve-stem key, comprising in combination, gripping jaws, a hook-device, means for forcing said hook-device into hooked engagement with said valve-stem key, comprising a screw, and cam means operated by said screw for actuating said gripping jaws into gripping engagement with said stem, said cam means acting to release said jaws when the hook-device is in hooked engagement with said valve-stem key.

14. A valve-cage remover for removing a valve-cage containing a valve and its stem, and valve-stem key, comprising in combination, jaws for gripping said valve-stem, a relatively-movable hook-device, means for moving said hook-device downwardly from said jaws, and cam means to actuate said hook-device into hooked engagement with said valve-stem key.

15. A valve-cage remover for removing a valve-cage containing a valve and its stem, and valve-stem key, comprising in combination, pivoted jaws for gripping said valve-stem, a relatively-movable hook-device, a screw operative to move said hook-device downwardly from said jaws, cam means to actuate said hook-device into hooked engagement with said valve-stem key, and cam means operated by said screw for actuating said gripping jaws.

16. A valve-cage remover for removing a valve-cage containing a valve and its stem, and valve-stem key, comprising in combination, jaws for gripping said valve-stem, a movable hook-device, a screw operative to move said hook-device upwardly and downwardly relative to said jaws, cam means to actuate said hook-device into hooked engagement with said valve-stem key, and cam means operated by said screw for actuating said gripping jaws during the downward movement of said hook-device into gripping engagement with said valve-stem, said cam means being inoperative to actuate said gripping jaws during the upward movement of said hook-device when being disengaged from said valve-stem key.

17. In a valve-cage remover for removing a valve-cage containing a valve and its stem, and valve-stem key, in combination, a frame, jaws mounted in said frame for gripping said stem, a hook-device mounted in said frame, means for forcing said hook-device into hooked engagement with said valve-stem key, comprising a hand-operated screw working in said frame, a second frame for supporting said first frame, and a hand-operated nut carried on said second frame for working on said screw to lift said first frame.

18. In a valve-cage remover for removing a valve-cage containing a valve and its stem, and valve-stem key, in combination, a frame, jaws pivotally mounted in said frame for

gripping said stem, a hook-device slidably mounted in said frame, means for forcing said hook-device into hooked engagement with said valve-stem key, comprising a hand-
5 operated screw working in said frame, cam means operated by said screw for actuating said gripping jaws, a second frame for supporting said first frame, and a hand-operated nut carried on said second frame for
10 working on said screw to lift said first frame.

19. A valve-cage remover for removing a

valve-cage containing a valve, its stem, valve-spring and valve-spring seat, comprising in combination, a device for effecting a 15 balanced hold at different sides of said valve stem by engagement therewith above said valve-spring seat, a jacking mechanism for lifting said device in a direction coaxial with the path of movement of said valve- 20 cage during its removal.

In testimony whereof I have affixed my signature.

RUSSELL W. MAGNA.
